1403

John Martineau, of
Joel Eastman, New Hampshire

Letters Patent

The Schedule referred to in these Letters Patent and making part of the same containing a description in the words of the said John Martineau, Administrator of the late Joel Eastman of the said Eastman many improvements in the arrangement and combination of wheels and other parts of a machine for the application of the power of horses and other animals.

To whomsoever these presents shall come
Be it known that John Martineau, of the town of Eldridge
County of Oneida and State of New York, Administrator of the
estate of Joel Eastman, deceased, in trust for his heirs & legal representatives in the
late Joel Eastman, in matter relating to the inventions and improvements
of the said Joel Eastman, ^{under the fact that the late Joel Eastman of New Hampshire} Administrator and maker of a
shortly before his decease invent an improvement in the arrangement
and combination of wheels and other parts of a machine for
the application of the power of horses or other animals for the
accomplishment of any objects for which such power is conveni-
ently applicable, commonly called a Horse Power a model of which
made by his (Joel Eastman's) own hands is herewith presented
showing its construction with accompanying drawings, description
and references wherein his improvement consists, some of
the objects or purposes to which this improved Horse Power is
applicable, are to drive threshing machines, cotton gins and
hemp mills. It may be applied to many other purposes.

The following is a full description of the arrangement and con-
nection of wheels, and other parts embraced in the construction
of the aforesaid Horse Power Machine which I will describe
separately, by reference to the accompanying drawings of the
various parts as well as may be to make myself understood.

Fig 1 is a ground or horizontal view of the machine. Fig 2. is

Drawing

a side view elevation and Fig. 3. an end view elevation. It may now be remarked, that in all the figures the same letters apply to corresponding parts of the Machine. A A A A. Fig. 1. shows the foundation timber longitudinal and the cross pieces under the wheels. The longitudinal pieces are connected in the centre and at the other end by cross pieces T. T. T. T. represents a horizontal shaft with a basal pinion on one end C. and on the other end is the drum or pulley I to receive the band that is to communicate motion to the threshing machine. Cotton Gin or other apparatus. K K. are Boxes in which the shaft runs and by which it is kept in its proper place. These Boxes are secured by screws boltz. O. O. D represents the bevel wheel geared into pinion C. The bevel wheel is hung on a right shaft or journal P which also receives pinion E shown in elevation fig. 2. which gears into two spun wheels E E. which last gear into a stationary wheel g. g. which is supported by two upright timbers I I. and iron braces J. J. J. The spun wheels E E are supported by journals m. m. which are provided with a projecting flange or collar on the lower end to keep the wheels from dropping off. The journals pass up through the cover H crossed by a strengthening piece L. They are provided with a shoulder that comes in contact with the lower side of the cover H and are firmly secured in their place by three screws thru' their upper ends counteracted by a metallic plate let into the wooden cover or strawing bar which at m. m. is provided with a ring bolt and clinch to attach the cover to H. O. O. is a horizontal piece of timber connected with L and provided with a hole in the centre through which the upright shaft or journal passes and by which it is steadied and supported in its position, partially, being assisted in no small degree by the wheel E E pinion, and the whole of them being action the stationary shaft G G are kept in their relative positions. I. S. when the collar or flanges on the journals m. m. that keep the wheel E E from dropping off. It is not intended necessary to give in writing the dimensions of the several parts above described as a sketch.

is appended to the drawing, which will readily explain, nor is it proper to limit the several parts to the dimensions herein laid down, they may be varied and should be adapted to the amount of power in any particular case intended to be applied.

The plan of the wood work may be varied, perhaps with advantage by substituting for the longitudinal pieces A A and C C, pieces T T, a single piece forming with large cross pieces A A as simple cross. The wheels E E may also be supported in their proper place by a cast iron bar, with pins or journals cast on solid or with a hole, and the journals made of wrought iron or steel and inserted and properly secured in their places by keys or screws and nuts. Nor is it necessary to limit the open wheel E E to two. Any additional one may be added, perhaps with advantage, making three open wheels, geared into the pinion F and stationary wheel G. These three open wheels may be hung on three arms connected at the centre and by a circular rim corresponding with the solid part of the stationary wheel G. To each of the arms a journal may be cast on solid, or be provided with a hole and have a wrought iron or steel journal inserted and secured as before observed or the whole may be made of wrought iron. Other details may also be varied to suit the taste of different persons.

If the iron rim as last described be used it may be provided with cheeks or brackets projecting upwards forming a birth for the reception of the drawing lever which would thus have room to spring across the whole diameter of the stationary wheel, constituting it a spring lever. When instead of an entire wooden drawing lever, with a cross steady piece supplied with iron journals as before described, a cast iron bar is used with solid journals cast on, or wrought or steel journals inserted.

The drawing lever may be attached thereto by two bolts, and when three open wheels are placed into the stationary wheel and pinion supported by a triplex arm connected with the centre and springing, a hole may be formed in the centre for the reception

the journal of the upright shaft P. the journals of all the wheels
pinion in that case being relatively ground. They cannot easily
be ground. In regard to the dimensions of the wheels and the mo-
tion of the drum or pulley it may be observed that a very suit-
able size for the stationary wheel G G. for all ordinary pur-
poses is from 34 to 40 inches diameter of pitch, axle and the
pinions from one sixth to one eighth of the same. The back wheel shall
be a little smaller say about six inches and its pinion bearing about the same
proportion to it. That pinion E bears to stationary wheel G G. The drum
or pulley L may be about 3 feet in diameter and revolve from fifty to six-
ty times for one revolution of the lever. There is a trifling variation in the
frame work from the model. in the latter the pulley or drum is
placed within the frame and the piece represented by L L in the model
is solid being joined solid with the longitudinal pieces A A. These
differences are merely noticed but are not deemed of any special importance.

What I claim as the invention of Joel Eastman, in trust
for his heirs and legal representatives is the combination of wheels, consist-
ing of stationary wheel G G and the wheels E E including a third
wheel if necessary, and pinion E all joined together. The improve-
ment effected by which arrangement is the advantage of bringing cog
into gear and action on opposite sides of the journal of the pinion
by means of which the stress is taken off the journal, and two or more
cogs being brought into action at the same instant the stress is divided
and distributed thereby diminishing the liability of breaking the cogs
in fact the strength by this arrangement when the cog on one side
is destroyed there is still a cog on the other side. It is doubtful whether if this wheel be used another advantage resulting
from this arrangement is compactness and portability.

There are other advantages that are derived from this application of
the foregoing claimed combination however the same may be modified in
pinions & pinion as it may be in the interest of the heirs and legal
representatives of the aforesaid lately deceased Joel Eastman
